UNITED STATES PATENT OFFICE.

THOMAS M. GREGORY, OF AKRON, OHIO.

DESIGN FOR A TOY BALLOON.

49,090.

Specification for Design.

Patented May 23, 1916.

Application filed October 25, 1915. Serial No. 57,891. Term of patent 14 years.

To all whom it may concern:

Be it known that I, THOMAS M. GREGORY, a citizen of the United States, residing at Akron, in the county of Summit and State of Ohio, have invented a new, original, and ornamental Design for a Toy Balloon, of which the following is a specification, reference being had to the accompanying drawing, forming part thereof.

The figure is a side view of a toy balloon, showing my new design.

I claim:

The ornamental design for a toy balloon, as shown.

THOMAS M. GREGORY.

Witnesses:

R. B. MOSER,
GEO. E. KRICKE.
